UNITED STATES PATENT OFFICE.

ELIAS J. ELIAS, OF OMAHA, NEBRASKA.

WIRE-STRETCHING MACHINE.

1,415,089.

Specification of Letters Patent. Patented May 9, 1922.

Application filed June 8, 1921. Serial No. 476,059.

To all whom it may concern:

Be it known that I, ELIAS J. ELIAS, a citizen of the United States, residing at Omaha, in the county of Douglas and State of Nebraska, have invented certain new and useful Improvements in Wire-Stretching Machines, of which the following is a specification.

The present invention relates to wire stretching machines adapted particularly for use in stretching the strands during fence construction.

An object of the present invention is to provide a relatively simple device which may be easily attached to a fence post and which may be used to advantage in stretching the barbed strands of wire forming the body portion of a fence.

Another object of the invention is to provide a machine of this character with means for preventing the twisting of the strands as the latter are drawn taut, thus preventing the disintegration and weakening of the strands and the destruction of the spurs 25 which are formed thereon.

The invention still further aims at the provision of a structure of this character which may be quickly and easily adjusted to fence posts of various diameters and 30 which may be rigidly clamped thereon.

The above and various other objects and advantages of this invention will be in part described in and in part understood from the following detailed description of the 35 present preferred embodiment, the same being illustrated in the accompanying drawing, wherein:

Fig. 1 is a perspective view of a wire stretching machine constructed according to the present invention and as mounted upon a fence post and having a wire strand attached thereto in position to be stretched.

Fig. 2 is a fragmentary sectional view, enlarged, of the head and the screw shaft connected thereto.

Fig. 3 is a top plan view of the device as applied to a fence post, parts being broken away.

Fig. 4 is an enlarged vertical section through one of the clamps employed for securing the wire strand to the device.

Referring to the drawing, 10 designates a fence post and 11 designates wire strands attached to the posts and forming therewith 55 the fence. The device for stretching the wire strands across the posts 10, embodies a

body plate 13 adapted to be arranged vertically and provided at its lower forward and rear corners with enlarged and internally threaded eye pieces 14 through which is supported a longitudinally extended shaft 15 which is threaded throughout substantially its entire length and which is considerably longer than the plate 13. The shaft 15 is provided upon its rear end with a crank 65 handle 16 or other suitable device by means of which the shaft 15 may be rotated in opposite directions.

The body plate 13 is provided with a seating jaw 17 upon its inner side and which has 70 an inner serrated or corrugated face presenting teeth adapted to bite into the adjacent side of the jaws 10 for holding the plate from slipping when subjected to pressure. The body plate 13 also has an inwardly extending arm 18 which is provided in its upper edge with a plurality of transverse spaced apart notches 18' adapted to receive therein the links of a chain 19, which chain is adapted to be drawn around the jaws 10 80 and has one end anchored in a screw eye 20 threaded through the plate 13 and through outstanding bracket or brace 21 carried by the plate. Fixed upon the outer end of the screw eye 20 is a crank handle 22 by means 85 of which the screw eye may be turned through the plate to draw the chain 19 more or less taut about the post 10.

The forward end of the shaft 15 is upset to provide an enlarged head 23 behind which 90 is rotatably mounted a collar 24, the latter having a concavity or race way 25 in its forward side to receive ball bearings 26 and the ball bearings being adapted to bear against the rear side of the head 23. The 95 collar 24 is held toward the head 23 by a transverse pin 27 which is secured through the shaft 15 and which bears against the rear side of the collar. Projecting forwardly from the collar 24 and about the head 23 100 is a yoke 28 having upon its forward end an upstanding and rearwardly directed hoop 29 over which is detachably engaged a staple or link 30 mounted upon a clamp 31. The clamp 31 is substantially of the structure 105 shown in Fig. 4 and is provided with a handle 32 rising from one side of the clamp 31 and fixed upon a rotatable shaft 33 extending transversely through the clamp and carrying an eccentric 34 which is adapted 110 to bind against the wire strand 11. A fixed jaw or anvil 35 is arranged transversely in

the lower part of the clamp and is adapted to receive the strand 11 thereagainst when compressed by the eccentric 34. The peripheral edge of the eccentric 34 is preferably 5 toothed or corrugated as at 36 for more firmly biting into the wire strand 11, and thus insuring the retention of the wire strand in the clamp. The clamp 31 has at one side an elongated anchoring arm 37 which 10 is of a length slightly greater than the usual distance between the lower strand and the ground and between the various superposed strands. This arm 37 is adapted to hold the clamp from turning and thus maintain 15 the wire from twisting when subjected to the tension required for drawing the wire taut. To aid in this anchoring of the arm 37, the latter may be provided with a rope or other flexible connector 38 attached to 20 the lower end of the arm 37 and extending transversely and rearwardly to the arm 18 of the body plate, the rope 38 being secured through a selected notch 18' of the arm 18 for holding the clamp substantially rigid.

25 The body plate 13 carries a second clamp 39 which is of similar form to the clamp 31 but which has at opposite sides depending projections or fork arms 40 which straddle the upper edge of the plate 14 and which 30 are detachably secured thereto by transverse bolts 41 secured through the arms 40 and the body plate 13. The eccentrics 34 of the clamps are normally urged toward the wire strand 11 by springs 42 which each have 35 one end connected to the hand lever 32 of the clamp and its other end connected to the body of the clamp. The clamps are released manually by forcing the handles 32, against the tension of the springs 42 for lifting the 40 eccentrics 34 out of engagement with the wire strand.

In use, the body plate is pressed against one side of a post 10 at such height as to dispose the shaft 15 substantially in line with 45 the strand 11 to be drawn taut. The screw eye 20 is turned backwardly through the plate and the chain 19 is secured in an adjacent notch 18'. The handle 22 is now turned for drawing the chain 19 taut about 50 the post. This tightening of the chain binds the block 17 firmly against the post and holds the body plate from swinging thereon. The wire strand 11 is threaded first through the clamp 31 and then through the clamp 39. 55 The hoop 29 of the yoke is engaged in the staple 30 of the clamp 31 for coupling the latter clamp to the shaft. The handle 16 is now turned to feed the shaft 15 rearwardly and draw the clamp 31 and the wire strand 60 11 secured therein for tightening the strand. As the arm 37 which is held by the flexible connector 38 engages an adjacent object, such as the ground or an adjacent wire strand, the clamp 31 is held from turning and consequently the wire strand 11 cannot widen

or be turned when subjected to tensional strain. When the shaft 15 is fed rearwardly to its fullest extent, the wire strand 11 is drawn through the clamp 39 and the shaft 15 may then be turned and fed forwardly 70 into its extended position. The clamp 31 is carried loosely over the strand 11 into proper position for securing a new grip upon the strand. The operation is again repeated until the desired tension is placed upon the wire 75 strand 11. When this is accomplished the screw eye 20 may be relaxed to loosen the chain 19 and the entire device be quickly removed from the post 10 and may be quickly applied to a second post.

80 It is an important feature to maintain the wire strand from twisting during the operation of drawing the wire strand taut. This is particularly useful in erecting the barbed wire fences as it prevents the destruction of the spurs or other projections which are carried by the strands.

85 It is of course understood that various changes and modifications may be made in the details of design, size, proportion and materials of the above specifically described embodiment without departing from the spirit of this invention, such changes and modifications being restricted only by the 90 scope of the following claims.

95 What is claimed is:

1. In a wire fence strand stretcher, a body portion provided with an arm adapted to engage across a post, a chain carried by the body portion adapted to engage about the post, said arm having means for adjustably receiving an end of the chain therein, means connected to the other end of the chain for drawing the same taut about the post whereby to bind the body portion against the post, a movable member carried by the body portion and a clamp mounted in the movable member adapted to engage a wire strand whereby upon operation of the movable member said strand may be drawn taut.

110 2. A wire stretcher comprising a body member, means for detachably securing the body member to a fence post, a threaded shaft mounted in the body member and having a head on its forward end, a collar rotatably mounted upon the shaft in rear of the head and having a yoke projecting outwardly about the head, a clamp detachably connected to the yoke and adapted to engage a wire strand, means for turning the shaft whereby 115 to draw the clamp and the wire strand toward the body member, said clamp having an extension arm thereon adapted to engage the ground for retaining the clamp from turning, and means for binding the strand to the body member during the return of said shaft and said first clamp.

120 3. A wire stretcher comprising a body plate having an inwardly extending arm adapted to extend across a fence post, a screw 130

eye threaded through the plate, a chain connected at one end to the screw eye and adapted for detachable connection with the arm at its other end, means for turning the screw arm to tighten said chain about the post and to bind said body plate thereagainst, a threaded shaft carried upon the body plate and being of greater length than the same and adapted to be turned for moving the shaft 10 axially through the plate, a yoke carried upon the outer end of the shaft, a clamp detachably connected to the yoke and adapted to engage a wire strand, and a second clamp mounted on the plate for engagement with 15 said wire strand whereby to hold the same taut during the shifting of said first clamp to obtain a new grip upon the wire strand.

4. A wire fence stretcher comprising a body plate having internally threaded eye 20 pieces at its lower corners, a seating block on its inner side adapted to engage against a fence post and an inwardly extending arm adapted to project across the side of the post, said arm having notches in its upper edge, a

screw eye threaded through the upper plate 25 and having a chain through its inner end adapted to engage about the fence post and detachably interlock in the notches of said arm, means for turning the screw eye to draw said chain taut about the post, an elongated 30 externally threaded shaft carried in said eye pieces, a yoke swivelly mounted upon the forward end of the shaft, means for turning the shaft to move said yoke toward and from the plate and a clamp detachably mounted 35 upon the outer end of said yoke and adapted for binding engagement with a wire strand, said clamp having an elongated arm projecting therefrom for contact with adjacent objects whereby to maintain the clamp from 40 turning during operation of the shaft.

In testimony whereof, I have affixed my signature in presence of two witnesses.

ELIAS J. ELIAS.
